UNITED STATES PATENT OFFICE.

EUSTACE CREES AND CHARLES S. COURT, OF PROVIDENCE, RHODE ISLAND, ASSIGNEES TO
J. S. TOWNSEND, OF CHICAGO, ILLINOIS.

DESIGN FOR A SPOON OR SIMILAR ARTICLE.

No. 38,897.

Specification for Design.

Patented Nov. 26, 1907.

Application filed September 9, 1907. Serial No. 392,073. Term of patent 14 years.

To all whom it may concern:

Be it known that we, EUSTACE CREES and CHARLES S. COURT, citizens of the United States, residing at Providence, in the county of Providence and State of Rhode Island, have invented a new, original, and ornamental Design for a Spoon or Similar Article, of which the following is a specification, reference being had to the accompanying drawing, forming part thereof, which drawing shows a plan view of the spoon.

I claim:

The ornamental design for a spoon, or similar article, as shown.

EUSTACE CREES.
CHARLES S. COURT.

Witnesses:

FREDERIC A. GREENE,
HOWARD E. BARLOW.
